UNITED STATES PATENT OFFICE.

EDWARD H. BUCKLEY, OF CALEDONIA, MINNESOTA.

CLUTCH.

1,116,985.

Specification of Letters Patent. Patented Nov. 10, 1914.

Application filed April 19, 1913. Serial No. 762,207.

To all whom it may concern:

Be it known that I, EDWARD H. BUCKLEY, a citizen of the United States, and a resident of Caledonia, in the county of Houston 5 and State of Minnesota, have made certain new and useful Improvements in Clutches, of which the following is a specification.

My invention relates to clutches, my more particular purpose being to provide an improved clutch adapted for use with a hay hoist of the kind actuated by aid of a horse, and in which the sweep or driven element of the clutch may be disconnected from the winding drum or driven element by a person accompanying the load to be hoisted, such person being at a distance from the sweep.

More particularly stated, my invention comprehends a clutch providing a revoluble drum, and with a cable to be wound by the rotation of said drum, a sweep normally connected with the drum for turning the same, and disconnecting mechanism controllable at a distance, and of special construction for rendering certain and positive the disconnection of the sweep.

Reference is made to the accompanying drawing forming a part of this specification, and in which like letters indicate like parts.

Figure 1 is a side elevation of the sweep and drum, and parts immediately associated therewith. Fig. 2 is a plan view of the mechanism shown in Fig. 1. Fig. 3 is a substantially central vertical section through the mechanism shown in Figs. 1 and 2.

A pair of sills are shown at 4, and extending upwardly from the latter are posts 5. Secured to these posts are side beams 6. 40 A cross beam 7 extends from one of the side beams 6 to the other. A revoluble drum is shown at 8 and is mounted upon a journal 9, the latter being secured rigidly upon a cross beam 10 forming a part 45 of the framework.

Rollers are shown at 11 and 12, and are revoluble relatively to the framework whereby they are supported. The journal 9 is provided with a reduced portion 13, 50 having the form of a stem, and extending directly upward. The drum 8 is provided with notches 14 arranged in the form of a circle, and spaced apart equidistantly, as indicated in Fig. 2. The notches 14 and 55 parts bounded thereby constitute an annular rack. A sweep is shown at 15 and is

provided with a hole 16 which fits over the stem 13, so that the sweep may turn relatively to the stem. The sweep 15 is further provided with an opening 17. Mounted upon the sweep is a bracket 18 and extending through this bracket and pivotally supported thereby is a lever 19. This lever is provided with a toe portion 20 which extends through the opening 17 and is 65 adapted to fit into any one of the notches 14. The lever 19 is provided with a fork 21, through which the stem 13 extends.

A spiral spring 22 encircles the stem 13 and engages the fork 21, this spring also 70 engaging the adjacent portion of the sweep 15. A sleeve 23 encircles the stem 13 and rests upon the fork 21. A cam lever 26 extends directly through the stem 13, which is slotted for this purpose; and is provided 75 with a cam surface 28. The sleeve 23 is provided with a raised portion 24, the latter being provided with a slot 25 into which the cam lever 26 may extend as indicated in Fig. 3.

A cord 29 is connected with the cam lever 26 and engages a pulley 30. This pulley is mounted upon a pivot pin 31. The hoisting line 32 is partially wound upon the drum 8 and engages the rollers 11, 12 for the purpose of guiding the line.

The hoisting line 32 is employed for raising the weight to be lifted which may consist of a quantity of hay or the like. The operator accompanying the load may, by 90 pulling upon the rope 29, rock the cam lever 26, and in doing this may depress the fork 21 and thus actuate the lever 19 so as to lift the toe portion 20 of this lever out of the notch 14 in which it happens to be at 95 the time.

The operation of my device is as follows: The parts being assembled and arranged as above indicated, the cord 29 is slackened so that the pressure of the spring 22 by acting 100 upon the lever 19 causes the toe portion 20 of this lever to enter some one of the notches 14. This being done, the sweep 15 is connected positively with the drum 8, and horses or other draft animals being harnessed to the sweep now turn the sweep so as to rotate the drum 8. The hoisting line 32 is thus wound up and the load is accordingly raised. The operator now pulls upon the hoisting line 29 so as to rock the lever 26. 110 This forces the sleeve 23 downwardly, compresses the spring 22, causes the lever 19 to

rock, and as a consequence this lever is disconnected from the drum 8, as above described.

Only one man is necessary in order to operate my device. Even in instances where it is desirable to employ two hands, the device still saves the work of one additional hand, otherwise employed to stop the travel of the horse. By disconnecting the sweep 10 from the drum, the continued travel of the horse can have no effect upon the winding mechanism.

By making the stem 13 integral with the journal 9, and mounting the cam lever 26 15 upon the stem 13, the construction of the mechanism necessary to accomplish the results desired is greatly simplified. Moreover, this construction is considerably compact, and other things being equal, stronger 20 than would usually be required.

I do not limit myself to the precise construction shown, as variations may be made therein without departing from the spirit of my invention, the scope of which is 25 mensurate with my claims.

I claim:

1. A device of the class described comprising a rigidly mounted journal having a portion forming a stem, a driven element rev-

olubly mounted upon the journal, a driving element revolvably mounted upon the stem, a lever carried by the driving element and provided at one end with means for engaging the driven element for locking it with the driving element, the opposite end 35 of the lever being bifurcated and being positioned to straddle the stem, a resilient member on the stem and engaging the bifurcated end of the lever, a sleeve loose on the stem and also engaging the lever, and a 40 cam lever carried by the stem for actuating the sleeve.

2. A device of the class described comprising a fixed shaft, a driven element revolvably mounted thereon, a driving element 45 also revolvably mounted thereon, a lever mounted on the driving element and having means for engaging the driven element for locking the driving and driven elements together, said lever being provided with a bifurcated portion straddling the shaft, and means on the shaft adapted to coöperate with the bifurcated portion for actuating the lever.

EDWARD H. BUCKLEY.
